UNITED STATES PATENT OFFICE.

WILLIAM MANN PRIZER, OF PHILADELPHIA, PENNSYLVANIA, ASSIGNOR TO WILLIAM MANN COMPANY, OF PHILADELPHIA, PENNSYLVANIA, A CORPORATION OF PENNSYLVANIA.

DESIGN FOR SAFETY PAPER.

Application filed April 13, 1929. Serial No. 30,877. Term of patent 14 years.

To all whom it may concern:

Be it known that I, WILLIAM MANN PRIZER, a citizen of the United States, residing in Philadelphia, Pennsylvania, have invented a certain new, original, and ornamental Design for Safety Paper, of which the following is a specification; reference being had to the accompanying drawing, in which the figure is a face view of a sheet of safety paper illustrating my design.

I claim:

The ornamental design for safety paper, substantially as shown.

WILLIAM MANN PRIZER.
